Primary Examiner — Catherine S Posthauer*Assistant Examiner* — Joan E. Diehl(57) **CLAIM**

The ornamental design for a card box as shown and described.

DESCRIPTION

FIG. 1 is a front perspective view of a card box showing my new design.

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view thereof, showing the card box in a position of use with exemplary cards.

The broken lines shown in FIG. 6 represent stitching, which forms part of the claimed design. The broken lines shown in the drawings depict portions of the card box and exemplary cards which form no part of the claimed design.
